UNITED STATES PATENT OFFICE

GEORGE D. OVERHOLTZ, OF FAIR OAKS, PENNSYLVANIA, ASSIGNOR TO McCLINTIC-MARSHALL COMPANY, OF PITTSBURGH, PENNSYLVANIA, A CORPORATION OF PENNSYLVANIA

OUTDOOR ADVERTISING STRUCTURE

Original application filed September 17, 1929, Serial No. 393,189. Divided and this application filed August 1, 1930. Serial No. 472,286.

This invention relates to improvements in outdoor advertising structures of the character embodying a steel framework, a poster panel construction supported by the framework, and a lattice structure associated therewith. The present invention particularly relates to a new and improved means for mounting and supporting the lattice on the structure, and is a division of my co-pending application Serial Number 393,189, filed September 17, 1929.

In outdoor advertising structures of the character stated, it is necessary to provide parts that may be readily erected and taken down; consequently, it is the practice to construct the framework of structural steel members that may be readily assembled and secured together, and to form the panel of detachable sections. The lattice structure designed to be employed with and be positioned immediately below the poster-receiving panel is usually of sheet metal construction. Heretofore, the erection or the assembling of the lattice on the structure and securing it thereto in the desired position, as well as dismantling the lattice, has been the source of considerable trouble and expense.

Among the objects of the present invention are, to provide simple and efficient means for mounting and detachably securing the lattice to the structure; to provide simple hanger members adapted to be attached to the framework of the structure and having means cooperating with means on the sectional lattice whereby said lattice sections may be readily positioned and detachably secured; and to provide a new and improved sectional lattice construction.

Further objects and advantages will become apparent from the following description taken in connection with the accompanying drawings, wherein:

Fig. 1 is a front elevational view of an outdoor advertising structure embodying my invention;

Fig. 2, a perspective view of the rear of two lattice sections, showing the manner of erecting;

Fig. 3, a vertical section taken on the line III—III of Fig. 1, particularly showing a

hanger and the co-acting means on the lattice section;

Fig. 4, a perspective view of the rear of an end lattice section, showing the means for attaching the same to the end capping 55 of a panel;

Figs. 5 and 6, perspective views showing different forms of a clip employed; and

Fig. 7, a view similar to Fig. 2, showing a modified form of erection means. 60

In the drawings, the poster-receiving panel is formed of several sections 2, joined edge to edge, and supported from a steel framework having uprights or posts 3 preferably formed of angle members. 65

A decorative molding 4 is secured around the border of the panel, and includes a bottom capping member 5 and side capping members 6, the latter extending below the panel proper, as at 7. This molding and capping may be formed of wood or sheet metal, and is secured to the framework of the panel in any suitable manner.

Positioned below the panel proper, and extending between the capping extensions 7, 75 I provide a metal lattice, generally designated A, and comprising several lattice sections B. Said lattice sections are preferably formed of sheet metal cut and bent into the shape of lattice work including, as illustrated, a plurality of vertically extending channel-like portions 8, and spaced apart openings 9 formed in the sheet between the adjacent portions 8. Said openings 9 are formed by stamping out portions of the metal 85 and bending the portions rearwardly of the channel-like portions 8, as at 10.

An important and characteristic feature of the present invention resides in the means for mounting and detachably supporting the several lattice sections B on the outdoor advertising structure, and, as illustrated and as preferred, these means include a series of adjustable hangers C designed to be positioned on the front faces of the uprights 3. The hangers are formed of a vertically extending member or element 11, preferably of flat strip or plate metal, and supporting members or angles 12, having flanges 13 thereof welded or otherwise secured to the member 11. The

members 12 are further formed with flanges 13a extending upwardly and parallel to the member 11, said flanges being provided with slotted openings 14 adapted to receive bolts 15 to secure the hangers to the uprights 3. Sections of angle bar 11a may be welded on the member 11 to space said member from the uprights 3 and to provide reinforcing therefor.

10 The lattice sections B, in addition to the parts above described, each includes longitudinally extending channel-like members 16 and 16a, the upper member 16 being located a slight distance below the upper edge of the lattice body and the lower member 16a being positioned adjacent its lower edge. These members are preferably secured by welding them to the body or to respective rows of the inwardly projecting fins or portions 10. The 15 channels 16 and 16a are flush with one end of the lattice sections, and extend beyond the other end thereof, as at 17. Slotted openings 19 are provided adjacent the ends of the channels for adjustably securing the lattice 20 sections together.

An angle member 18 is welded or otherwise secured to the under side of the upper flange of channel member 16, at a predetermined distance inwardly from the ends thereof. Similarly, the channel 16a is provided with an angle member 18a secured to the lower flange thereof. It will be noted, however, that the angle member 18a is offset or 30 out of alignment with the angle member 18. This arrangement is very important as it permits the assemblage of the sections to be made with the least possible trouble, as hereinabove described. The angle members 18 and 18a extend rearwardly from their respective 35 channels, and have one flange a thereof spaced away from the channel members a slight amount, as shown in Fig. 3.

In some instances, the said angle members 18 and 18a are formed integral with and extend substantially the length of the respective channels 16 and 16a, and are provided with offset openings to function similarly to the offset members 18 and 18a. Thus, in the 40 form of Fig. 7, the channels 16 and 16a are formed with integral opposed flanges 18b and 18c respectively, said flanges extending the length of the channel members. Offset openings x and y are provided in the flanges 18b and 18c respectively, for receiving the ends 45 b and b' of a hanger member 11 during the act of assembling.

It will be noted that the channel members stiffen the flexible lattice body, thus providing a very desirable construction for handling these sheet metal sections, and that the 50 said channels and the elements carried thereby cooperate with the hangers C for mounting and securing the lattice sections to the structure.

65 Clips 20 are provided for finally securing

the lattice to the panel structure. These clips are box-like, and are provided with a lattice engaging member 21, a panel capping engaging flange 22, and side members 23. The member 21 is formed with a slotted opening 24 and the flange 22 is provided with an opening 25. The flange 22 is adapted to be bent, as indicated in Figs. 5 and 6, for a purpose hereinafter described.

Several of these clips 20 with their flanges 22 bent outwardly away from the side members 23 are bolted in the upper ends of the vertically extending channel-like portions 8 of the lattice sections, as indicated at c, said flanges being flush with the tops of said portions. The lattice sections B and the hanger brackets C may be elevated until the flanges 22 engage the under side of the bottom capping 5, said movement being permitted by means of the slotted openings 14 of the hanger brackets. Screws or bolts 26 are entered into the openings 25 of the clips and secure the lattice to said capping. I have shown a wooden member as one form of capping, but obviously a metal capping may be used, necessitating rows of slotted openings therein for receiving the bolts 26.

Clips 20 are also secured in the outer ends of the lattice channels 16 and 16a of the end lattice sections, said clips having their flanges 22 bent in the direction of the side members 23, as shown in Fig. 6. Screws or bolts 27 are entered into the openings 25 thereof for securing said end sections to the side capping extensions 7, as particularly shown in Fig. 4.

When the lattice sections have been elevated and secured to the capping, the sections are securely fastened together by means of bolts and slotted openings 19 in the lattice 105 channels. Also, the bolts 15 of the hanger brackets may be finally tightened to secure said brackets to the uprights 3.

In assembling the sectional lattice on the structure, assuming that the hangers C have been positioned on the respective uprights 3, one section at a time is temporarily or loosely positioned by causing the angle members 18 or 18a, or their flanges a, to overlap and engage the respective ends b and b' of the vertically extending member 11 of the lattice hanger. The length of the members 18 and 18a are such as to permit of a lateral or sliding movement of the section, and owing to the offset position of these members relatively to each other, as above described, it will be understood that the upper member 18 will be brought into engagement with the end b of member 11 before the member 18a engages the end b, thus aiding in the assembling by properly guiding the section while it is being slid along.

So, also, in the form of Fig. 7, the opening x in the flange 18b permits engagement of the lattice section B or its flange 18b with the

end *b* of the hanger C, whereby the same is suspended and may be moved laterally, so that the lower end *b'* of said hanger may be entered in the opening *y* and the flange 18*c* 5 engage the end *b'* of the hanger.

Extensions 17 of the channels 16 and 16*a* may be telescoped in the channel ends of an adjacent lattice section, and temporarily bolted together by means of the slotted openings 19 therein.

Thus, it will be seen that the entire lattice may be temporarily positioned below the panel proper. By means of the slotted openings 19 of the channels 16 and 16*a*, the lattice 15 may be "stretched" to fill the space between the end capping extensions 7.

After the temporary positioning, as above described, the lattice is finally positioned and secured in the final position by means of the 20 clips 20 and their cooperating fastenings.

If desired, a molding or apron D may be secured to the lattice sections B by means of bolts 28 and spacers 29. The apron D preferably extends beyond one end of the lattice 25 sections for telescoping with adjacent apron portions, as will be readily understood.

I claim:

1. In an outdoor advertising structure, the 30 combination with a member of a support framing, a sheet metal lattice associated with the structure, a vertically extending hanger secured to an upright of the support framing, said lattice having a transversely extending channel member secured thereto and 35 having means thereon cooperating with the vertically extending hanger for supporting the lattice.

2. In an outdoor advertising structure, the 40 combination with a supporting framing having a vertically extending post, a panel portion and a molding for the panel, of a sectional sheet metal lattice associated therewith, means for mounting and securing the lattice sections to the structure including a 45 vertically extending hanger secured to the post, a reinforcing channel secured to a lattice section having means cooperating with the hanger, clips mounted on the lattice section, and means for securing the clips to the 50 molding.

3. In an outdoor advertising structure, the 55 combination with a supporting framing having a vertically extending post, a panel portion and a molding for the panel, of a sectional sheet metal lattice associated therewith, means for mounting and securing the lattice sections to the structure including a 60 vertically extending hanger secured to the post, an upper and a lower transversely extending channel member carried by each lattice section, cooperating engaging means on the channel members and the vertically extending hanger, and clips carried by the lattice section for securing the section to the 65 molding.

4. In an outdoor advertising structure, the combination with a supporting framing having a vertically extending post, a panel portion and a molding for the panel, of a sectional sheet metal lattice associated therewith, means for mounting and securing the lattice sections to the structure including a 70 vertically extending hanger secured to the post, an upper and a lower transversely extending channel member carried by each lattice section, cooperating engaging means on the channel members and the vertically extending hanger, and clips carried by the lattice section for securing the section to the molding, said channel members each having 75 an apertured end projecting beyond the section and an apertured end substantially flush with the section.

5. In an outdoor advertising structure, the combination with a member of a support framing, a sheet metal lattice associated with the structure, a vertically extending adjustable hanger secured to an upright of the support framing, said lattice having a transversely extending channel member secured thereto and having means thereon cooperating with the vertically extending hanger for supporting the lattice.

6. In an outdoor advertising structure, the 95 combination with a member of a support framing, a sheet metal lattice associated with the structure, a vertically extending hanger secured to an upright of the support framing, said hanger including a vertically extending member and an angle support member having a flange thereof slotted, said lattice having a transversely extending channel member cooperating with the hanger for supporting the lattice on the hanger.

In testimony whereof I affix my signature.

GEORGE D. OVERHOLTZ.
